GAS TURBINE JET PROPULSION ENGINE

This invention concerns a gas turbine jet propulsion engine. According to the present invention, in its broadest aspect, there is provided a gas turbine jet propulsion engine having conduit means in which are arranged in flow series combustion equipment and variable area nozzle means, a fuel supply control unit for controlling the supply of fuel to the said combustion equipment, nozzle area adjustment means for varying the area of the said nozzle means, measuring means for measuring the dynamic pressure in the conduit means upstream of the said combustion equipment, and control means, which are acted upon by said measuring means, for controlling the nozzle area adjustment means.

In its preferred form, the present invention provides a gas turbine jet propulsion engine having compressor means, main combustion equipment, turbine means and first nozzle means in flow series; variable area second nozzle means which receive compressed air from at least part of the compressor means via conduit means which bypass the main combustion equipment and turbine means; nozzle area adjustment means for varying the area of the second nozzle means; additional combustion equipment for burning fuel in the said conduit means; a fuel supply control unit for controlling the supply of the said fuel, measuring means for measuring the dynamic pressure in the conduit means upstream of the additional combustion equipment, and control means which are acted upon by said measuring means and which control the nozzle area adjustment means.

The said measuring means may also comprise means for measuring a pressure functionally related to the dynamic pressure at the second nozzle means when fuel is supplied to the additional combustion equipment.

The control means may control the nozzle area adjustment means in such a way as to maintain a substantially constant relationship between the said dynamic pressures in the conduit means and at the second nozzle means.

The control means may comprise a bellcrank lever mounted on a fulcrum, the two arms of the bellcrank lever being respectively subjected by said measuring means to forces which tend to rotate the bellcrank lever in opposite angular senses about the fulcrum.

The bellcrank lever may control the output of a pump adapted to supply hydraulic liquid to control the nozzle area adjustment means.

The invention is illustrated, merely by way of example, in the accompanying drawing, which shows a gas turbine jet propulsion engine according to the present invention.

In the drawing, there is shown a gas turbine jet propulsion engine 1 having an engine casing 2 within which there are mounted in flow series a low pressure compressor 3, a high pressure compressor 4, main combustion equipment 5, a high pressure turbine 6 which drives the high pressure compressor 4 through a shaft 7, and a low pressure turbine 9 which drives the low pressure compressor 3 through a shaft 10.

The air compressed by the low pressure compressor 3 passes into a plenum chamber 11 and part of this air passes therefrom via conduits 12, 13 (which bypass the main combustion equipment 5 and turbines 6, 9) to two diametrically spaced-apart progressively variable area front nozzles 14, 15 respectively which are under the control of hydraulically operated nozzle area adjustment rams 18, the front nozzles 14, 15 being rotatable to vary the direction of the efflux therefrom, whereby to "vector" the thrust. Combustion equipment which includes fuel injectors 16, 17, are provided in conduits 12, 13 respectively to enable this thrust to be increased when desired, e.g. when used to effect vertical takeoff.

The turbine exhaust gases pass via conduits 20, 21 to two diametrically spaced-apart rear nozzles 22, 23 which are also rotatable to vary the direction of the efflux therefrom.

The fuel injectors 16, 17 are supplied with fuel, via pipes 25, 26, from an annular manifold 27. The annular manifold 27 is supplied with fuel through a fuel duct 33 which extends to the high pressure side of a vapor core centrifugal pump 34.

5 The pump 34 has a fuel inlet 35 the communication between which and the "eye" of the pump is controlled by an inlet throttle 36. The inlet throttle 36 is constituted by a sleeve whose interior may receive fuel from the fuel inlet 35. The inlet throttle 36 is movable towards and away from a valve seat 37 by a fuel control supply unit 38 which is responsive (by means not shown) to at least one engine variable and which is controlled by the setting of a manually operable pilot's lever 39.

15 A piston 40, to which is connected a linkage 41, is movable in a cylinder 42, the piston 40 having oppositely disposed pressure surfaces 43, 44. The pressure surfaces 43 is open to supply of fluid at a high pressure, e.g. to the fuel supplied to the main combustion equipment 5 by way of a duct 45. The pressure surface 44 is open to the pressure in a duct 46 which communicates with the duct 45 by way of a restriction 46'.

20 The linkage 41 is connected to a swash plate 47 of a swash plate pump 48 so that movement of the piston 40 adjusts the inclination of the swash plate 47 and hence the output of the pump 48. The high and low pressure sides of the pump 48 are connected by pipes 49 to the rams 18 so that the inclination of the swash plate 47 controls the positions of the rams 18 and so controls the areas of the front nozzles 14, 15.

25 The duct 46 communicates with a chamber 50 by way of a variable restriction 51 whose size depends upon the axial position of a valve rod 52, the chamber 50 being connected to a low pressure source. The valve rod 52 is connected for axial movement to one arm 53 of a bellcrank lever 53, 54. The valve rod 52 is provided with a gear 55 which meshes with an engine driven gear 56. The valve rod 52 is then continuously rotated in operation so as to help to prevent it from sticking, whereby it will move readily on any change in the forces acting on the bell crank lever 53, 54.

30 It will thus be appreciated that movement of the bellcrank lever 53, 54 will adjust the position of the valve rod 52 and will therefore adjust the pressure in the duct 46 and hence the pressure acting on the pressure surface 44. This will cause appropriate adjustment in the position of the piston 40 and hence of the areas of the front nozzles 14, 15.

35 The bellcrank lever 53, 54, which is pivotally connected by a link 60 to the wall of a housing 61, is movable about a fixed fulcrum constituted by a roller 62 mounted on a rod 59. The arms 53, 54 of the bellcrank lever are subjected to two forces which tend to rotate the bellcrank lever in opposite angular senses about the roller 62, these two forces being transmitted to the bell crank lever 53, 54 from diaphragms 63, 64.

40 The housing 61 contains chambers 65, 66, 67. The chambers 65, 66 are separated from each other by the diaphragm 63, and the chambers 66, 67 are separated from each other by the diaphragm 64. The chambers 65, 66 communicate with each other by way of restriction 68.

45 The chamber 65 communicates via a restriction 69 with a duct 70 which is open to atmosphere.

The chamber 66 communicates with a duct 73, which is arranged to receive the total pressure prevailing at a point 73' immediately upstream of the region in which the fuel is burned at the fuel injectors 16, 17, the mass flow through the point 73' being substantially the same as that through the nozzles 14, 15.

50 Since fuel is supplied to the fuel injectors 16, 17 only at or near top speed, the front nozzles 14, 15 will be choked at this time and the dynamic head thereat will therefore be a fixed fraction of the total pressure. Accordingly, the pressure acting on the diaphragm 63 at this time will be functionally related to the dynamic pressure at the fuel injectors 16, 17 and thus will also be functionally related to the dynamic pressure at the front nozzles 14, 15.

55 The chamber 67 communicates with one end of a duct 74 whose opposite end is arranged concentrically about the duct 73 and receives the static pressure at the point 73'.

The force on the diaphragm 64 is therefore representative of the dynamic head at the point 73', i.e. at a point upstream of the fuel injectors 16, 17.

As will be appreciated if the ratio between the dynamic pressures at the front nozzles 14, 15, and that at the point 73' varies from that which balances the bellcrank lever 53, 54, movement will occur of the bellcrank lever 53, 54 about its roller 62 and this will cause axial movement of the valve rod 52. The pressure in the duct 46 and so on the surface 44 will alter, with the result that the rams 18 will vary the areas of the front nozzles 14, 15. This will in turn vary the back pressure acting on the low pressure compressor 3 in such a way as to tend to restore the bellcrank lever 53, 54 to its original position.

I CLAIM:

1. A gas turbine jet propulsion engine having compressor means, main combustion equipment, turbine means and first nozzle means in flow series; variable area second nozzle means which receive compressed air from at least part of the compressor means via conduit means which bypass the main com-

bustion equipment and turbine means; nozzle area adjustment means for varying the area of the second nozzle means; additional combustion equipment for burning fuel in the said conduit means; a fuel supply control unit for controlling the supply of the said fuel, measuring means for measuring the dynamic pressure in the conduit means upstream of the additional combustion equipment and for measuring a pressure functionally related to the dynamic pressure at the second nozzle means when fuel is supplied to the additional combustion equipment, and control means which are acted upon by said measuring means and which control the nozzle area adjustment means in such a way as to maintain a substantially constant relationship between the said dynamic pressures in the conduit means and at the second nozzle means.

15 2. An engine as claimed in claim 1 in which the control means comprises a bellcrank lever mounted on a fulcrum, the two arms of the bellcrank lever being respectively subjected by said measuring means to forces which tend to rotate the bellcrank lever in opposite angular senses about the fulcrum.
